United States Patent Office

Des. 189,784
Patented Feb. 21, 1961

189,784

DRESSER

Ernest L. Swarts and Orville B. Solie, Rockford, Ill.,
assignors to The Lane Company, Inc., Altavista, Va.,
a corporation of Virginia

Filed Nov. 2, 1959, Ser. No. 58,169

Term of patent 14 years

(Cl. D33—6)

The figure is a front perspective view of a dresser showing our design.

The end not shown is like the end shown, while the back is conventionally plain.

The dominant feature of the design resides in the particular arrangement of the front face of the dresser in combination with the drawer pulls, substantially as shown.

We claim:

The ornamental design for a dresser, as shown and described.
